UNITED STATES PATENT OFFICE.

WALTER LENCHARD, OF MCKEESPORT, PENNSYLVANIA.

TOY PIN-BOARD.

1,352,137.

Specification of Letters Patent. Patented Sept. 7, 1920.

Application filed October 17, 1919. Serial No. 331,435.

To all whom it may concern:

Be it known that I, WALTER LENCHARD, a citizen of the United States, residing at McKeesport, in the county of Allegheny and State of Pennsylvania, have invented new and useful Improvements in Toy Pin-Boards, of which the following is a specification.

This invention relates to games, and more particularly to a game of the pin board type.

One of the main objects of the invention is to provide a game apparatus of the character stated of simple construction and operation which may be readily produced and sold at small cost. A further object is to provide simple and efficient means for setting the device by means of which a plurality of members, or a single member, may be moved into set or operative position. Another object is to provide simple and efficient means for releasing movable plates or cover members to indicate the points to which a player is entitled. Further objects will appear from the detailed description.

In the drawings:—

Figure 1 is a top plan view of a game apparatus constructed in accordance with my invention.

Fig. 2 is a side view of the same.

Fig. 3 is a fragmentary detail section.

Fig. 4 is a fragmentary sectional view taken substantially on line 4—4 of Fig. 1.

The apparatus includes a base or board 1 provided with a peripheral vertical wall or flange 2 of sheet metal. A bridge piece 3 extends across board 1 adjacent one end thereof and is provided in its upper edge portion with a plurality of vertically disposed bores 4 which slidably receive plungers 5 normally held in depressed position by expansion springs 6 positioned within the bores and confined between the plungers and a cap strip 7 secured over the upper edge of bridge 3. Plunger 5 presses upon a latch 8 pivoted at 9 for vertical movement in a slot 10 in the bridge. This latch carries a catch 11 which projects forwardly therefrom and is adapted to engage over a tongue 12 extending upwardly from a disk 13 provided at its bottom with spaced sleeves 14 by means of which it is pivotally attached to a setting rod 15 rockably supported by hinge leaves 16 secured to the front of bridge 3. A substantially U-shaped wire spring 17 is coiled about rod 15 adjacent the outer face of each of the sleeves 14, the bight portion of this

spring passing inside of disk 13 above the rod so as to tend to rock the disk downwardly and outwardly from the bridge. The rod 15 extends through wall or flange 2 and is provided with a rectangularly disposed setting arm 18 downward movement of which is positively limited by a stud 19 projecting from the flange. The rod is further provided with a plurality of upwardly directed arcuate setting fingers 20, these fingers being operable between the sleeves 14 of the disks.

The board is provided with a plurality of pins 21 which are arranged in rows transversely of the board, the pins of the rows being relatively staggered. An inclined trough or chute 22 is attached to the end of the board remote from bridge 3 and is so positioned as to discharge a ball rolled down the chute toward the forward or bridge end of the board centrally thereof. This ball is intended to roll between the pins 21 so as to drop through any one of a plurality of openings 23 provided adjacent the inner face of bridge 3 for this purpose, the board being supported in an inclined position by suitable supports 24, as in Fig. 2. When the ball drops through any one of the openings 23, it strikes the inner end portion 25 of a trigger lever 26 pivoted midway its ends in a U-bracket 27 secured to the under face of board 1. The outer end portion 25^a of lever 26 presses against the lower end of a trip rod 28 slideable in a vertical bore in bridge piece 90 3 which is coaxial with bore 4, the rod bearing against the under surface of latch 8. A stop finger 29 carried by lever 26 inwardly of the pivot thereof engages the under face of board 1 so as to provide a positive stop 95 for limiting downward movement of rod 28. When the ball strikes the inner portion 25 of the lever the outer end portion 25^a is forced upwardly thus raising latch 8 through the medium of rod 28 and releasing disk 13 which is moved by spring 17 into a substantially horizontal position, in which position it is held by a finger 20. Each disk 13, when in raised position, covers a number or other symbol having an arbitrary value, and the player is credited with point in accordance with the particular disk which is released as the result of his playing. As will be understood, certain of the spaces covered by the disks may be marked to indicate that the player is "out" thus losing his right to play. Also, of course, any desired values may be

given to the different spaces and the game may consist of any number of points desired. The disks or covers which have been released may be readily moved into raised or operative position by rocking rod 15, the fingers 20 of which are in engagement with these disks serving to rock the same with the rod into vertical position so as to be engaged by the catches 11 and releasably held thereby. 10 The rod 15 acts in this manner as a pintle for supporting the various disks and also, together with the fingers 20, provides means for positively limiting downward and outward movement of the disks and for raising the same into vertical or set position. 15

What I claim is:

1. In a game apparatus, a board provided with a plurality of openings for passage of a game piece, a bridge member, a plurality of disks pivotally mounted adjacent said bridge member for movement toward and away from the same, means for releasably securing said disks in raised position, means actuatable by a game piece passing through said openings for releasing said disks, and means for pivotally supporting the disks and for returning the same to raised position.

2. In a game apparatus, a board having a plurality of openings for passage of a game piece, a bridge piece carried by said board, a plurality of disks positioned adjacent the bridge piece, means for releasably holding said disks in raised position, means for pivotally supporting the disks for movement toward and away from the bridge piece and for positively limiting downward movement of the disks when released and returning the disks to raised position, and means actuatable by passage of a game piece through any one of said openings for releasing said disks.

3. In a game apparatus, a board provided with a plurality of openings for passage of a game piece, a bridge attached to said board, a rod rockably mounted upon the board, a plurality of disks mounted upon said rod adjacent one face of the bridge and movable into parallelism with and closely adjacent thereto, a plurality of setting fingers carried by the rod and positioned for contact with the disks for moving the same into position adjacent the bridge when the rod is rocked toward said bridge, means for

releasably securing the disks in raised position, and means actuatable by passage of a game piece through the openings for releasing said disks.

4. In a game apparatus, a board provided with a plurality of openings for passage of a game piece, a bridge piece extending transversely of the board adjacent said openings, a rod rockably mounted upon said bridge piece, disks pivotally attached to said rod so as to be movable toward and away from the bridge piece, spring pressed catches for engaging the upper portions of said disks for releasably holding the same in raised position, rods slidable through the bridge and engaging beneath said catches, trip levers pivotally suspended beneath the board and having their inner end portions projecting beneath said openings and their outer end portions in contact with the lower ends of said rods, upward movement of the inner end portions of said levers being positively limited, and a plurality of setting fingers projecting from said rod and positioned for contact with the respective disks when the rod is rocked toward the bridge for raising said disks.

5. In a game apparatus, a board provided with a plurality of openings for passage of a game piece, a bridge piece extending transversely of the board adjacent said openings, a rod rockably mounted upon said bridge piece, disks pivotally attached to said rod so as to be movable toward and away from the bridge piece, springs pressed catches for engaging the upper portions of said disks for releasably holding the same in raised position, rods slidable through the bridge and engaging beneath said catches, trip levers pivotally suspended beneath the board and having their inner end portions projecting beneath said openings and their outer end portions in contact with the lower ends of said rods, upward movement of the inner end portions of said levers being positively limited, and a plurality of setting fingers projecting from said rod and positioned for contact with the respective disks when the rod is rocked toward the bridge for raising said disks, and means for turning said rod and positively limiting rocking movement thereof in a direction away from the bridge.

In testimony whereof I affix my signature.
WALTER LENCHARD.
